APPARATUS FOR ENAMELING ARTICLES

Clas S. Larson and Walter A. Kuebler, Milwaukee,
Wis., assignors to A. O. Smith Corporation, Mil-
waukee, Wis., a corporation of New York

Application August 3, 1935, Serial No. 34,513

4 Claims. (Cl. 214—17)

This invention relates to apparatus for enameling articles such as large sections of pipe of the order of forty feet or more in length as employed in underground pipe lines for the long distance transmission of oil and gas. Such pipe is preferably covered with a coating of vitreous enamel for the purpose of preventing corrosion from the soil. The application of vitreous enamel to pipe sections of this character has raised certain problems never before encountered in an enameling plant. One of these problems results from the size and weight of the article which requires that all handling be done by machinery, it not being uncommon for a section of pipe to weigh well over one ton; and another results from the size and length of the pipe sections, requiring that the fusing of the enamel be done while the pipe is in a vertical position rather than horizontal, since in the latter position it would be difficult, if not impossible, to support the pipe against sagging at the high fusing temperature required without destroying the coating.

The object of the present invention is to provide an apparatus constituted of a single machine for applying the vitreous enamel coating to an article such as pipe.

Another object is to provide simple and efficient apparatus for continuously and progressively performing the steps required in vitreous enameling sections of pipe and like articles.

Other objects will appear hereinafter.

This application is closely related to the following: application for Enameling machines, Serial No. 628,654, filed by Clas S. Larson on August 13, 1932; patent for Enamel spraying booth, No. 2,026,080, granted to Adam Ziska; patent for Pipe handling apparatus, No. 2,010,820, granted to Clas S. Larson; application for Compensators for hoisting apparatus, Serial No. 623,478, filed by Otto E. Uecker on July 18, 1932; application for Elevator for conveyor trucks, Serial No. 34,511, filed by Walter A. Kuebler on August 3, 1935; application for Elevator for conveyor systems, Serial No. 34,512, filed by Clas S. Larson and Walter A. Kuebler on August 3, 1935; and an application for Conveyor truck, Serial No. 31,988, filed by Clas S. Larson on July 18, 1935; all of which are assigned to a common assignee with the present application.

The preferred embodiment of the present invention is illustrated in the accompanying drawings in which:

Figure 1 is a schematic elevational layout of the machine circuit;

Fig. 2 is a diagrammatic view of the path of the trucks;

Fig. 3 is a side elevation showing the drive for the several conveyors and elevators;

Fig. 4 is a top plan view showing the drive as illustrated in the left half of Fig. 3;

Fig. 5 is a top plan view complementary to Fig. 4 and showing the drive as illustrated in the right half of Fig. 3;

Fig. 6 is a longitudinal section showing the 10 conveyor track, a truck and the main chain;

Fig. 7 is a schematic plan view of the machine circuit;

Fig. 8 is a transverse sectional view of apparatus shown in Fig. 6;

Fig. 9 is a top plan view of apparatus shown in Fig. 6, parts being broken away;

Fig. 10 is a side elevation illustrating the transfer of a truck from one horizontal conveyor chain to another;

Fig. 11 is a transverse section taken on line 11—11 of Fig. 10;

Fig. 12 is a transverse section of the apparatus showing an elevator;

Fig. 13 is a longitudinal section of the apparatus 25 and is taken on the line 13—13 of Fig. 12; and

Fig. 14 is a section taken on line 14—14 of Fig. 12.

The machine in its general outline, as illustrated in Figures 1 and 7, follows the outline of 30 the process for treating the pipe in which the enameling mixture is first applied to the surface of the pipe, then it is dried and preheated, and then fused in a furnace at a fusing temperature such as 1550° F., after which the pipe and enamel coating are either cooled slowly, or are quenched in a fluid to cool the same rapidly and give desirable properties thereto as set forth in Patent No. 1,919,136 issued to L. R. Smith on Enamelled metal articles and method of producing them. 40

The pipe section 1 is first tipped from horizontal position to vertical position by suitable mechanism at 2 and which is set forth and claimed in detail in Patent No. 2,010,820, above referred to. As the pipe swings to vertical position it becomes attached to a truck 3, to be described later, and which is set forth and claimed in copending application Serial No. 31,988, referred to above. It is then picked up by the first elevator 4 and as it is drawn upwardly for 45 its whole length it passes through the spraying booth 5 and receives a thin coat of enameling material on the outside.

The detail construction of the spraying booth 5 is set forth and claimed in Patent No. 2,026,080

referred to above. Upon passing of the pipe through the spray booth 5, the truck 3 from which it is suspended reaches the upper or main conveyor level. The truck and pipe are then 5 moved horizontally through the drying and pre-heating oven 6 at the end of which it reaches the second elevator 7 which lowers it to the furnace level, the pipe 1 being lowered through an opening 8 in the top of the furnace 9 while 10 the truck 3 is disposed above the furnace. The pipe 1 is then moved horizontally through the furnace at a rate which will produce the desired fusion of the enamel by the time the pipe reaches the end of the furnace. Two openings 15 are provided in the furnace at the discharge end; one opening 10 being in the top and being for removal of the pipe upwardly by elevator 11 should it be desired to cool the pipe slowly, the other opening 12 extending in alignment 20 through both top and bottom of the furnace to provide for lowering the section of pipe bodily into a quenching tank 13 beneath the discharge end of the furnace.

Elevator 14 is provided for lowering the pipe 25 from the furnace into the quenching bath and the details of construction of this elevator are more fully set forth and claimed in application Serial No. 34,512 above referred to. During quenching the pipe is moved horizontally in the 30 tank 13 and is then removed upwardly by elevator 15 to the furnace level, but outside of the furnace. It is then moved horizontally to elevator 16 which moves it upwardly to the upper main conveyor level, the same as it would have 35 been had it been drawn out of the furnace by elevator 11, without quenching. In either event, the pipe is then moved horizontally through a slow cooling chamber 17 to elevator 18 where it is lowered onto an unloading cradle 19 similar 40 to the mechanism 2 and which removes the pipe from truck 3 and swings the pipe to horizontal position where it is removed from the machine as a finished product.

Fig. 1 shows a side elevation of the machine 45 as though the path of movement of the pipe is from left to right in more or less of a straight line. However, the machine, as built, provides a continuous circuit as illustrated in Fig. 7 where the drying oven and cooling chamber are arranged at opposite ends of the conveyor, the 50 loading, spraying and unloading are on one side, and the furnace and quenching tank are on the other. Any suitable arrangement of circuit may be provided.

55 As shown generally in Figs. 1, 3, 4 and 5, the horizontal conveyor system comprises a main conveyor 20 at the top of the structure, a furnace conveyor 21, a conveyor 22 for moving the pipe through the quenching tank, a conveyor 23 60 and an auxiliary conveyor 24 at the end of the furnace for transferring the pipe between elevators, and a transfer conveyor 25 for transferring the empty trucks 3 from the unloading mechanism 19 to the loading mechanism 2. The 65 details of construction of the several conveyors are much alike, and are shown in Figs. 6, 8, 9, 10 and 11.

In the main conveyor circuit 20, the trucks 3 70 are mounted on a pair of rails 26 which extend throughout the path of movement of the trucks in that circuit. The trucks 3 are propelled along the rails 26 by a continuously moving endless chain 27 which is suspended at short intervals by means of trolleys 28 from a track 29 located 75 above the trucks. Each trolley 28 is provided

at its underside with pivoted hooks 30 adapted to engage lugs 31 on the top of a truck 3. The truck 3 is released from the hook 30, as the former reaches an elevator which is adapted to lower the truck, by means of stationary blocks 5 32 supported from the main frame of the machine and which are located in the path of the hook 30 so that as the latter engages the block, the hook is raised out of engagement with the lugs 31. When a truck is raised by an elevator 10 to the level of conveyor 20, the hook 30 automatically engages the lugs 31 as the hook moves slowly over the top of the truck.

For the purpose of raising or lowering the trucks at the elevators, the rails 26 are interrupted at the several elevators and short elevator rails 33 are provided for supporting the trucks during vertical movement, as will be described in more detail hereinafter in connection with Figs. 12 to 14. It will be noted that the 20 main conveyor 20 is at the top of the machine and that the trucks 3 are not raised to a higher level since the chain 27 prevents any raising of the trucks. The trucks are moved upwardly to the rails 26 or downwardly therefrom, as may be 25 desired.

The furnace conveyor 21 is constructed differently from the main conveyor 20 in that the trucks 3 are lowered onto the conveyor or raised from it. The conveyors 21, 23 and 24 are arranged end to end in overlapping relation as illustrated in Figs. 1, 3, 10 and 11. A single pair of rails 34 is provided for supporting the truck during horizontal movement along these conveyors. In conveyor 21 instead of one conveyor 35 chain, two endless chains 35 are provided, one on either side of the trucks. The chains are arranged beneath the trucks and are provided with upwardly extending hooks 36 for engaging lugs 37 on the trucks.

As the trucks reach the end of conveyor 21, and should it be desired to lower the trucks to the quenching conveyor 22, the trucks are transferred to conveyor 23 which moves them onto the elevator 14 for lowering.

The conveyor 23 has a pair of endless chains 38 operating in parallel above the path of the trucks and having downwardly extending hooks 39 for engaging lugs 40 on the trucks. The chains 38 overlap the chains 35 sufficiently to effect engagement of the lugs 40 by hooks 39 prior to the release of the lugs 37 from hooks 36.

The chains 35 travel on sprockets 41 and the chains 38 travel on sprockets 42, the sprockets being arranged vertically so that the release of 55 lugs 37 is effected by the dropping of chains 35 and hooks 36 over the sprocket 41 and away from the truck 3, and the engagement of lugs 40 by hooks 39 is effected by the lowering of the chain 38 and hooks 39 over sprocket 42 and into the 60 horizontal path of the lugs 40.

The quenching conveyor 22 is constructed similar to furnace conveyor 21 and need not be separately described.

The auxiliary conveyor 24 is also constructed 65 similar to the furnace conveyor 21 and is adapted to receive a truck from the end of conveyor 23 and transfer the same to the elevator 16 for raising to the main conveyor 20. The raising of the article from the quenching bath to the main conveyor level is taken in two steps, first from the quenching conveyor 22 to the transfer conveyor 23 by elevator 15, and then from the auxiliary transfer conveyor 24 to the main conveyor 20, by elevator 16.

After the truck has been lowered by elevator 18 and relieved of its load by mechanism 19, it is transferred by conveyor 25 to the elevator 4 where it is loaded with another pipe section and 5 starts through the circuit again.

The general construction of elevator 4 is shown in Figs. 12 to 14. The other elevators are similar in construction. The elevator shown is the same at that set forth and claimed in application Serial No. 34,511, above referred to. Various embodiments might be employed. For instance, the elevator set forth and claimed in application Serial No. 628,654, above referred to, might be used. As preferred, the elevator has a carriage 44 supporting the short rail sections 33, and adapted to be raised or lowered in vertical guides 45. The vertical movement of the carriage is effected by two pairs of endless chains 46 operating on opposite sides of the carriage and 20 each pair having a crosshead 47 connected to support the carriage. The chains 46 pass over and are driven by sprocket wheels 48 at the top of the elevator shaft, and pass under sprocket wheels or shoes 49 at the bottom of the shaft. 25 As the chains 46 travel in synchronism the crosshead 47 secured to the chains on opposite sides of the carriage 44 moves up and down, thus effecting vertical movement of the carriage 44 and rail section 33.

30 As illustrated in Figs. 3, 4, and 5, the several parts of the machine are all driven from a single source of power mechanically connected to each part. In this way all parts of the machine are kept in synchronism, it being impossible for any 35 part to get out of step with the others.

The loading mechanism 2 and unloading mechanism 19, however, are driven by separate motors 50 and 51, respectively, each of which is controlled by limit switches in circuit with a synchronizing switch 52 operated by the transfer conveyor 25, as illustrated in detail in Patent No. 40 2,010,820, above referred to.

The main drive motor 53 for the machine is located at the top and is connected by suitable speed reducing gearing 54 to the main drive shaft 55 which extends for nearly the full length of the machine. A small motor 56 is preferably provided to operate the machine at slow speed for adjusting and is connected to the main motor shaft by the speed reducer 57 and a clutch 58, see Fig. 4. A brake 59 is provided for the motor 53 to effect rapid stopping of the same.

At one end of the shaft 55 it is connected through a suitable speed reducer 60 and gearing 55 61 to a large horizontal sprocket wheel 62 which drives the main conveyor chain 27. The sprocket wheel 62 is at one end of the circuit of chain 27 and determines the path of the chain at that end. At the other end of the circuit, the chain 27 60 passes around a shoe 63 which is adjustable to effect tightening or loosening of the chain.

The elevator 4 is driven directly from main shaft 55 through the bevel gears 64, horizontal shaft 65, bevel gears 66 at each end of the shaft 65 65, vertical shafts 67, and gears 68 which drive the upper sprocket wheels 48. Elevators 7, 11, 14, 15, 16 and 18 are similarly driven from bevel gears 69, 70, 71, 72, 73 and 74, respectively, on the main drive shaft 55. Elevator 11 has a clutch 75 70 provided in its drive for the purpose of disconnecting the elevator when it is desired to use elevators 14, 15 and 16. A clutch 76 is provided in main shaft 55 for disconnecting the left end of the shaft and prevent operation of elevators 14, 75 15 and 16 when it is desired to use elevator 11.

Elevator 14, which lowers the pipe from the furnace into the quenching bath has a special safety feature which permits continued lowering of the pipe so as to get the truck 3 out of the hot furnace should the machine stop for any reason 5 midway in the lowering of a pipe section. As shown, a clutch 77 is provided in the drive for the elevator 14 similar to clutch 75 for elevator 11 for the purpose of disconnecting elevator 14 from the drive. A brake 78 is provided on the elevator 14 to permit lowering of the elevator slowly as desired.

The furnace conveyor 21 is driven from the gear box 79 on the main shaft 55, through the horizontal shaft 80, bevel gears 81, vertical shafts 15 82 and gears 83 which are connected to drive the sprocket wheels 41 at one end of the conveyor.

The conveyors 22, 23 and 24 are driven from the gear box 84 through vertical shaft 85 and suitable connections therefrom to the sprocket wheels 20 of the respective conveyor chains.

The conveyor 25 is driven from gear box 86 on the main drive shaft 55, through the horizontal shaft 87, bevel gears 88, vertical shaft 89 and gears 90 connected to drive the sprocket wheels 25 for the conveyor chains.

By providing a single complete drive by which all parts are operated in synchronism and in continuous movement, a very efficient enameling 30 operation is obtained, since each successive article will be treated exactly alike and there will be but slight variation, if any, in quality of the finished product.

The invention may have various embodiments 35 within the scope of the accompanying claims.

We claim:

1. In a machine of the class described, a pair of horizontal rails defining a conveyor path, means to lower a truck onto said rails for movement therealong, an endless chain or the like disposed parallel to said rails and beneath said truck having means thereon for engaging said truck and moving the same along said rails, said chain passing downwardly to a return circuit to release 45 said truck prior to reaching the end of said rails, a second endless chain disposed above said truck and adapted to engage the same and continue its movement on said rails as said first named chain releases said truck, and means disposed in the 50 path of said truck as it is propelled forwardly by said second named chain for lowering said truck from said conveyor path, rails and chain.

2. In a machine of the class described, a pair of horizontal rails defining a conveyor path, means 55 to raise a truck to the level of said rails for movement therealong, an endless chain disposed above said truck and extending parallel to said rails, means on said chain for engaging said truck to move the same onto and along said rails, a second 60 endless chain disposed beneath the path of said truck and having means to engage the truck and to continue its movement forward on said rails as the truck is released from said first named chain, and means disposed at the end of the path 65 of the first mentioned chain for elevating the truck from the level of said rails.

3. In a machine of the class described, a pair of horizontal rails defining a conveyor path, means to lower a truck onto said rails for movement therealong, an endless chain or the like disposed parallel to said rails and beneath said truck having means thereon for engaging said truck and moving the same along said rails, said 70 chain passing downwardly to a return circuit to 75

release said truck prior to reaching the end of said rails, a second endless chain disposed above said truck and adapted to engage the same and continue its movement on said rails as said first named chain releases said truck, means disposed in the path of said truck as it is propelled forwardly by said second named chain for lowering said truck from said conveyor path, rails and chain, and means for driving said chains and last named means in timed relation to effect the continuous movement of the truck.

4. In a machine of the class described, a pair of horizontal rails defining a conveyor path, means to raise a truck to the level of said rails for movement therealong, an endless chain disposed

above said truck and extending parallel to said rails, means on said chain for engaging said truck to move the same onto and along said rails, a second endless chain disposed beneath the path of said truck and having means to engage the truck and to continue its movement forward on said rails as the truck is released from said first named chain, means disposed at the end of the path of the first mentioned chain for elevating the truck from the level of said rails, and means for driving said chains and last named means in timed relation to effect the continuous movement of the truck.

CLAS S. LARSON.
WALTER A. KUEBLER. 15
